UNITED STATES PATENT OFFICE.

HARRY J. KEATING, OF CHICAGO, ILLINOIS.

PERFUMING APPARATUS.

1,137,632.

Specification of Letters Patent. Patented Apr. 27, 1915.

Application filed April 20, 1914. Serial No. 833,208.

To all whom it may concern:

Be it known that I, HARRY J. KEATING, a citizen of the United States, residing at Chicago, in the county of Cook and State 5 of Illinois, have invented a certain new and useful Improvement in Perfuming Apparatus, of which the following is a full, clear, concise, and exact description, reference being had to the accompanying drawings, 10 forming a part of this specification.

My invention relates to perfuming or disinfecting apparatus and has for its object the provision of improved means for delivering a blast of treated air into a confined 15 space, such for instance as would be found in telephone booths, transfer buses, taxicabs, street cars or the like.

My invention is not designed to deliver a liquid spray, but is designed to deliver 20 a blast of air or gas which has been passed through a suitable liquid by which the air is charged with an agent such as it is desired to deliver.

In the description herein I will describe 25 my invention more particularly as it is applied to deliver periodically a blast of air which has been passed through a perfuming liquid, thus to avoid the objectionable odors found in confined spaces.

To this end my invention when applied in 30 this particular form consists of a device having a pump periodically actuated by a door or similar element to force air through a supply of liquid and to direct this air into 35 the confined space.

I will describe in detail this particular form which my invention may take by referring more particularly to the accompanying drawing, in which—

Figure 1 shows a portion of a telephone 40 booth as provided with my improved device; Fig. 2 is a vertical sectional view of my improved device, and Fig. 3 is a sectional view on lines *a—a* of Fig. 2.

Referring more particularly to Fig. 1, I 45 show a telephone booth 1 having the customary door 2. My improved device 3 is attached at any suitable space within the booth and is operated periodically as the door is closed through the agency of the operating lever 4. This operating lever co-operates with a metallic plate 5 secured to the door, which metallic plate engages the upper left hand extremity of the lever to

move it from one position to the other once 55 during each time the door is closed.

My improved device 3 is made in the form of a receptacle and is adapted to contain perfumed or otherwise treated liquid 6. Within the receptacle the pump 7 is mounted, being held in place by a suitable band 8 and resting on top of the brackets 9. The pump has the customary piston 10 which is attached by means of the link 12 with the arm 13 of the bell crank lever 4. This bell 65 crank lever 4 is pivoted upon a cotter pin 14, which cotter pin engages a suitable bracket 15. This bracket 15 is fastened within the receptacle and protrudes through the cover plate 16 thereof. It will be seen that the 70 arm 13 is of a flattened C-shape so that it may rest on top of the rounded upper surface of the bracket 15. A further cotter pin 17 pivotally unites the arm 13 with the link 12. 75

In Fig. 2 I show in full lines the position of the elements in one position and show them in their alternate position in dotted lines. A tube 11 extends from the lower portion of the pump down into the liquid 80 and near the bottom thereof. Now whenever the piston 10 is moved downwardly it forces air through the tube 11, which air bubbles through the liquid 6 and is thereby suitably charged and is then emitted from 85 the openings 18 in the cover plate 16. A spring 19 having one extremity within an opening 18 and its other extremity between the opposite sides of the arm 13 normally retains the bell crank lever 4 in the position 90 shown in full lines in Fig. 1. A suitable closure or cap nut 20 is provided through which the device may be suitably filled.

It will be seen that as the door actuates the bell crank lever 4 that a jet of treated 95 air emanates from the openings 18 and is discharged into the booth 1, thus to cause the air therein to assume a more pleasing odor.

My improved device consisting of the receptacle as shown has a downwardly projecting finger 21 adapted to rest within the flattened C-shaped extremity 22 of a back 23. A finger 24 at one portion of this back extends forwardly to hold the device more 105 thoroughly in place. The upper extremity of the receptacle has a flange 25 so that by means of the screws 26 it can be secured to

the back 23. The back of course is held in place upon the wall in any suitable manner, and a bracket 27 extending forwardly of the back likewise helps to hold the container in 5 place.

From what has been described my invention will be clear. It will also be clear that it is susceptible of modification without departing from its spirit.

10 Having however thus described one form which my invention may take, what I claim as new and desire to secure by Letters Patent is:

1. A device of the character described comprising a liquid container, a pump within the container, means whereby said pump when actuated forces air through said liquid, and openings in said container through which the treated air is emitted.

20 2. A device of the character described comprising a liquid container, a pump within the container, means whereby said pump when actuated forces air through said liquid, and openings in said container through 25 which the treated air is emitted in jets through the agency of the pressure supplied by said pump.

30 3. A device of the character described comprising a liquid container, a pump within the container, means whereby said pump when actuated forces air through said liquid, openings in said container through which the treated air is emitted, and a door actuating lever for periodically operating said pump.

35 4. A device of the character described comprising a liquid container, a pump within the container, means whereby said pump when actuated forces air through said liquid, 40 openings in said container through which the treated air is emitted in jets through the agency of the pressure supplied by said pump, and a door actuating lever for periodically operating said pump.

45 5. A device of the character described

comprising a liquid container, a pump within the container, means whereby said pump when actuated forces air through said liquid, 50 openings in said container through which the treated air is emitted, a door actuating lever for periodically operating said pump, and a spring for restoring said lever.

6. A device of the character described comprising a liquid container, a pump within the container, means whereby said pump 55 when actuated forces air through said liquid, openings in said container through which the treated air is emitted in jets through the agency of the pressure supplied by said pump, a door actuating lever for periodically 60 operating said pump, and a spring for restoring said lever.

7. A device of the character described comprising a liquid container, a pump within the container, means whereby said pump 65 when actuated forces air through said liquid, openings in said container through which the treated air is emitted, a door actuating lever for periodically operating said pump, a spring for restoring said lever, and a 70 bracket upon which said container is mounted.

8. A device of the character described comprising a liquid container, a pump within the container, means whereby said pump 75 when actuated forces air through said liquid, openings in said container through which the treated air is emitted in jets through the agency of the pressure supplied by said pump, a door actuating lever for periodically 80 operating said pump, a spring for restoring said lever, and a bracket upon which said container is mounted.

In witness whereof, I hereunto subscribe my name this 19th day of March, A. D., 85 1914.

HARRY J. KEATING.
